UNITED STATES PATENT OFFICE.

AUGUSTUS H. JONES, OF MERIDEN, CONNECTICUT, ASSIGNOR TO THE CHARLES PARKER COMPANY, OF SAME PLACE.

EXTENSION LAMP-FIXTURE.

SPECIFICATION forming part of Letters Patent No. 271,334, dated January 30, 1883.

Application filed December 12, 1882. (No model.)

To all whom it may concern:

Be it known that I, AUGUSTUS H. JONES, a citizen of the United States, residing at Meriden, in the county of New Haven and State of Connecticut, have invented certain new and useful Improvements in Extension Lamp-Fixtures; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to devices for attaching pulleys and pulley-arbors to the suspending brackets or hangers of extension-lamps. Heretofore the bearing-posts for said arbors have been drilled to receive the same, and the arbor ends protruding through the holes thus made have been hammered to head them, and thus prevent detachment. This method is tedious and expensive, and it involves the use of malleable metal for the arbors, whereas the utmost hardness is desirable. I avoid these disadvantages by setting the ends of the pulley-arbors into open recesses in the tops of the bearing-posts and securing them there by a cross-bar, which is clamped upon the tops of said posts and provided with depending lips or flanges, which prevent the endwise motion of said arbors.

In the accompanying drawings, Figure 1 represents a side view of a pulley-hanger or bracket provided with devices embodying my invention. Fig. 2 represents a detail view of the cross-bar, and Fig. 3 represents a transverse section through one of the pulleys and the proximate devices.

A designates the hanger, which consists of a metallic frame provided on opposite sides, near its top, with bearing-posts *a a*, arranged in pairs and recessed on top to receive in each pair the arbor *b* of one of the pulleys *B*, used for the chains whereby the lamp and weight are suspended.

C designates a cross-bar, which is bifurcated at each end, so as to leave space for said pulleys and the chains passing over them, although

said cross-bar bears against the top of each post *a* and prevents the said arbors from rising out of said posts. Said cross-bar is provided with flanges or lips *C'*, which prevent the endwise motion of the said arbors by extending down on the outside of said posts and opposite, respectively, to the ends of said arbors. This cross-bar has a central opening, and there is a central opening also in the bottom of the hanger *A*. Through these openings, and through a corresponding opening in the lower end of a suspending-loop, *D*, extends a rod or stem, *E*, which is provided with a shoulder, *E'*, below said hanger, and with screw-threads *e* above the lower bar of said loop. A nut, *F*, turned home on said screw-threads, clamps said loop, cross-bar, and bracket firmly together, and thereby closes the bearings of the pulley-arbors. By turning off said nut all the aforesaid parts are readily separated.

The hardest material attainable may be used for the pulley-arbors, as no modification of their form is required in putting the parts together, and they will then be far better suited to withstand the considerable strain of the lamp and weight than if made of metal that can be headed like a rivet. There is also no need to drill any of the devices used. The arbors do not become permanent portions of the hanger, as after riveting, but may easily be separated therefrom.

The same method of attachment may be applied to the arbors of pulleys used on shades or lamp-supports, when such are used.

Having thus fully described my invention, what I claim as new, and desire to secure by Letters Patent, is—

1. In an extension lamp-fixture, a pulley provided with a detachable arbor, in combination with a bracket or hanger having bearings for said arbor, and devices which hold said arbor to said bearings and prevent its separation from said pulley.

2. A pulley-hanger provided with bearing-posts which are recessed on top, in combination with pulley-arbors which set into said recesses, and a bar extending across said hanger, which is clamped to the tops of said bearing-posts.

3. A pulley and its arbor, in combination with a hanger having bearings for said arbor, and a bar clamped against said bearings, said bar being provided with lips which extend opposite the ends of said arbor, and thus prevent its endwise motion.

4. A bracket A, suspending-loops D, cross-bar C, pulleys B, and arbors b, all clamped to-

gether by a bolt, E, and nut F, substantially as set forth.

In testimony whereof I affix my signature in presence of two witnesses.

AUGUSTUS H. JONES.
